UNITED STATES PATENT OFFICE.

RUSSELL P. EDWARDS, OF HIGHLAND PARK, MICHIGAN.

WHEELED TOY.

1,261,798.

Specification of Letters Patent. Patented Apr. 9, 1918.

Application filed February 12, 1917. Serial No. 148,183.

To all whom it may concern:

Be it known that I, RUSSELL P. EDWARDS, a citizen of the United States, residing at Highland Park, in the county of Wayne 5 and State of Michigan, have invented certain new and useful Improvements in Wheeled Toys, of which the following is a specification.

This invention relates to improvements in 10 toys and more particularly to wheeled motor propelled toys.

The object of the invention is to provide a simple, cheaply constructed, light toy of 15 this character which is designed especially for the amusement of small children.

This invention consists in the matters hereinafter set forth and more particularly pointed out in the appended claims.

In the accompanying drawings:

20 Figure 1 represents a side elevation of a toy constructed in accordance with this invention,

Fig. 2 is a longitudinal section taken on the line 2—2 of Fig. 3.

25 Fig. 3 is a plan view thereof with the body shown by the dotted lines.

In the embodiment illustrated a driving shaft or axle 1 is shown having wheels 2 and 3 fixed to its opposite ends, said wheels 30 being preferably composed of sheet metal such as tin and the like to adapt the device to be cheaply constructed. These wheels are preferably constructed out of tin disks with cut-out portions 4 formed therein to 35 lighten the structure and with their peripheral edges bent to form tread flanges 5.

An elongated U-shaped frame 6, braced intermediate of its ends by cross bars 7, has the free ends or terminals of the legs there- 40 of loosely engaged with the shaft 1 by any suitable means. A cross bar 8 preferably connects and braces the free ends of this frame 6 as is shown clearly in Fig. 3.

45 Adjustably mounted on the cross bar 9 of the rear end of frame 6 is a wheel carrying member 10 which is here shown substantially heart-shaped in form with a small wheel 11 rotatably mounted thereon, and with the apex of said heart connected with 50 the cross bar 9 of frame 6 to move laterally in either direction, and to be secured in adjusted position by means of a bolt 12 and nut 13, the member 10 being clamped between the nut 13 and the upper face of the 55 cross bar 9 as is shown clearly in Fig. 1. It will thus be seen that this wheel 11 which

operates as a guide for directing the course of the toy may be shifted laterally to one side or the other of the longitudinal axis of frame 6 and secured in position by tightening the nut 13 or it may be positioned in a straight line therewith as shown in Fig. 3.

This heart-shaped wheel carrying frame or member 10 is preferably curved longitudinally downward as shown in Figs. 1 and 65 2, and frame 6 is also shown slightly curved longitudinally although it need not necessarily be so formed, provided its front end be disposed in a plane below axle 1.

A body 14 is mounted on the frame 6 70 and held thereto by any suitable means and may be used for holding articles to be conveyed from one place to the other or for any purpose for which it may be desired. This body 14 is also shown curved longitudinally to conform to the curvature of frame 6, and when it is employed for holding ballast for retaining the wheel 11 in engagement with the surface over which the device is propelled the weight of said bal- 80 last will be below the plane of the axle 1, and the force thereof will be used to assist in knocking down or upsetting any article or articles which may be disposed in the path of the toy, it being especially designed 85 as a battle ship or battering ram for knocking down toy soldiers, buildings and the like.

This toy is preferably propelled by a spring motor which is here shown in the form of a spiral spring 15 mounted on one 90 side of the frame 6 and which is designed to be wound up by a key (not shown) and to exert its propelling force in unwinding for driving the toy which is accomplished through means of a gear 16 mounted on the 95 spring casing and revolute therewith and which meshes with a smaller gear 17 mounted on a stub shaft 18 which projects laterally from the side of the frame 6. This gear 17 meshes with a pinion 19 fixed to the 100 shaft 1 so that when the spring 15 unwinds it will operate to rotate shaft 1 through said gears 16 and 17 and the pinion 19, thereby rapidly propelling the wheels 2 and 3 of the toy, so that when it comes in contact 105 with an obstructing object considerable force will be exerted thereby, sufficient to overturn small objects such as toy soldiers, and the like.

From the above description it will be obvious that this toy may be cheaply made and easily operated, and that its impelling

force may be utilized for any purpose other than that above mentioned, and that the weight of any articles carried by the body 14 will operate to hold the toy in contact 5 with the surface over which it is driven.

When it is desired that the device shall travel in a circle or in a curved path the wheel 11 is moved laterally to one side or the other according to the direction in which 10 it is desired said toy shall move and secured in said position by means above described.

It will be understood that the above description and the accompanying drawings comprehend only the general and preferred 15 embodiment of the invention and that various minor changes in details of construction, proportion or arrangement of the parts may be made within the scope of the claimed 20 invention without sacrificing any of the advantages thereof.

I claim as my invention:—

1. A toy vehicle of the class described comprising a driving shaft, a pair of wheels fixed to the opposite ends thereof, a transversed braced longitudinally and downwardly curved U-shaped frame having the ends of its legs loosely engaged with said shaft, a body carried by said frame and curved to conform to the curvature thereof 25

with one end disposed over said driving shaft and the other positioned in a plane below it, a rearwardly extending downwardly curved member mounted for lateral adjustment on the cross bar of said U-shaped frame, a guiding wheel carried by 30 said member, and means for propelling said vehicles.

2. A toy of the class described comprising a driving shaft, a pair of wheels fixed to opposite ends of said shaft, an elongated U-shaped body supporting frame having the free ends thereof loosely engaged with said shaft between said wheels, a body carried by said frame and having its rear ends disposed in a plane below said shaft, a substantially heart-shaped member having its apex pivotally mounted on the cross bar of said frame, a wheel mounted to turn between the lobes of said heart-shaped frame, and propelling means connected with the 45 driving shaft.

In testimony whereof I affix my signature in presence of two witnesses.

RUSSELL, P. EDWARDS.
